US0D1032351S

(12) **United States Design Patent** (10) **Patent No.:** **US D1,032,351 S**
(45) **Date of Patent:** **** Jun. 25, 2024**

(54) **CLAMP**

(71) Applicant: **Shenzhen Linsky Intelligent Control Technology Co., Ltd**, Shenzhen (CN)

(72) Inventor: **Xingjia Zheng**, Shenzhen (CN)

(73) Assignee: **Shenzhen Linsky Intelligent Control Technology Co., Ltd**, Shenzhen (CN)

(**) Term: **15 Years**

(21) Appl. No.: **29/874,220**

(22) Filed: **Apr. 17, 2023**

(30) **Foreign Application Priority Data**

Feb. 10, 2023 (CN) 202330041874.1

(51) **LOC (14) Cl.** **08-08**

(52) **U.S. Cl.**
USPC **D8/396**

(58) **Field of Classification Search**

USPC D8/394-396, 71-74
CPC B25B 5/06

See application file for complete search history.

Primary Examiner — Janice Hallmark

(57) **CLAIM**

The ornamental design for a clamp, as shown and described.

DESCRIPTION

FIG. 1 is a front, right and top perspective view of a clamp showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view in its use state; and,

FIG. 10 is an enlarged detail view of encircled portion 10 in FIG. 1.

The broken lines in the figures illustrate portions of the clamp that form no part of the claimed design.

1 Claim, 10 Drawing Sheets
